UNITED STATES PATENT OFFICE.

ARTHUR S. LICHTEN, ABRAHAM KOUFMAN, AND WILLIAM SHULIK, OF PHILADELPHIA, PENNSYLVANIA.

TROUSERS.

Application filed October 17, 1927. Serial No. 226,736.

Our invention relates to a new and useful improvement in trousers and it relates more particularly to a novel construction in the art of making trousers whereby the inner flap or buttonhole band or strip heretofore commonly employed on the front flap of trousers, is entirely eliminated and whereby, moreover, not only is said buttonhole band or strip eliminated but the front buttons of the trousers are also eliminated.

Our invention further relates to a novel construction in trousers whereby the front of the trousers is closed by means of a fastening device, preferably of a continuous character, such as described, for instance, in United States Letters Patent No 1,219,881, secured to the inner surface of the flap at a suitable distance from the edge thereof so as to be entirely concealed from view.

Our invention further consists of a novel construction in trousers, whereby the flap of the trousers is reinforced or stiffened by means of a suitable interior lining ply or haircloth, or the like, and whereby the thus reinforced or stiffened flap is secured to the opposed edge of the front opening of the trousers, by means of a fastening device spaced a suitable distance inwardly of the free edge of the flap; said flap being caused to lie flat against the body of the trousers in all positions or postures of the wearer or of the user by virtue of the novel construction thereof.

Our invention relates more particularly to an improvement in trouser flaps of the character disclosed in our co-pending application, Serial No. 208,678, filed July 27th, 1927, whereby the fastening means is concealed not only from without by the outer reinforced or stiffened flap, but whereby said fastening means is also concealed or shielded from within by means of a novel form-retaining, inner flap of our novel construction, so as to prevent any contact between said fastener and the body of the wearer or the undergarments.

For the purpose of illustrating our invention, we have shown in the accompanying drawings one form thereof which is at present preferred by us, since the same has been found in practice to give satisfactory and reliable results, although it is to be understood that the various instrumentalities of which our invention consists can be variously arranged and organized and that our inven-

tion is not limited to the precise arrangement and organization of the instrumentalities as herein shown and described.

In the accompanying drawing, in which like reference characters represent like parts, 80

Figure 1 represents a front elevation of a fragmentary portion of trousers embodying our invention.

Figure 2 represents a similar view in elevation, showing the interior of the trousers. 65

Figure 3 represents a fragmentary view in front elevation similar to that shown in Figure 1, somewhat enlarged, however, and with the outer cloth ply of the flap cut away, in order to expose to view the novel interior 70 construction thereof.

Figure 4 represents a section on line 4—4 of Figure 3, showing the construction of the flap.

Figure 5 represents a section on line 5—5 75 of Figure 3, also illustrating the construction of the flap and its relation to the body of the trousers.

The two front halves 1 and 2 of the trouser instead of being united by the usual 80 double front flap heretofore commonly employed, with the inner flap provided with a row of buttonholes and a corresponding row of buttons on the opposed half of the front of the trousers, is merely provided with 85 a pair of opposed single fold flaps 3 and 4, along the juxtaposed vertical edges of the two halves 1 and 2 respectively, of the trousers, between which flaps 3 and 4 a continuous fastening device is provided in a concealed manner. 90

The front flap 3 is composed of the cloth 5 composing the trousers, which is folded at 6 upon itself to provide an inturned edge 7. An inner lining fabric ply 8 is provided 95 with an inturned edge 9, suitably stitched to the inturned edge 7 of the cloth 5 by means of the row of vertical stitches 10 in a manner shown particularly in Figure 5.

A stiffening ply 11 is interposed between 100 the cloth 5 and the lining fabric 8, with the outer vertical edge of said stiffening ply extending in between the body of cloth 5 and the inturned edge 7 thereof so as to stiffen the flap 3 to the outermost edge 6 105 thereof.

The fastening device employed may be of any suitable form although the one particularly illustrated is of the type described in the United States Letters Patent No. 1,219,- 110

881. This fastening device comprises chiefly two juxtaposed and staggered rows of metallic fasteners 12 and 13 arranged vertically of the flap. Each of the rows of fasteners 12 and 13 is carried by a narrow strip or band of fabric 14 and 15 respectively.

The fastener band 14 is first stitched to the lining 8 and to the reinforcing ply 11 by means of a row of vertical stitches 15, along 10 the inner edges both of said lining and reinforcing plies and said band 14. A binder tape 16 is then folded about the free edges of said fastener tape 14, stiffening ply 11 and lining ply 8, and suitably secured by 15 by a row of vertical stitches 17. A fourth row of vertical stitches 18 extending through the two folds of the binder tape 16 as well as through the fastener band 14, lining ply 8 and stiffening ply 11 as well as through 20 the cloth 5, secures the fastener and lining assembly to the front cloth body 5 and thus completes the front half 1 of the trousers with the vertical row of fasteners 12 disposed a suitable distance inwardly of the 25 outer edge 6 of the front flap 3 and substantially parallel thereto.

The stiffening ply 11 of the front flap 3 may be of any suitable material although in the preferred embodiment of our invention a fabric is employed which is composed 30 of a set of limp cotton or other vegetable fibre threads interlaced with a second series or set of relatively stiff hair strands at right angle to the first set of limp threads. 35 This stiffening ply 11 thus composed of the set of cotton threads 19 and the set of hair threads 20 is arranged with the cotton extending vertically or substantially parallel to the edges of the flap 3 or longitudinally 40 thereof and with the hair threads 20 extending horizontally at right angle or transversely of the flap 3. By this means a greater transverse stiffness is imparted to the flap 3, together with a lesser longitudinal 45 stiffness.

The cloth 21 of the opposed half 2 of the front of the trousers is folded back upon itself at 22. The rear flap 4 is composed chiefly of the stiffening fabric ply 23 of 50 suitable width, and extending vertically, and preferably formed of duck or the like, which is lined front and back with the lining fabric 24 folded around the free edge of the stiffening ply 23 at 25, so as to form a 55 front layer 26. A row of stitches 27 extending parallel to the edge 25 and through the lining plies 24 and 26 and the intermediate duck stiffening ply 23, serves to secure the edge of the stiffening ply to the two folds 60 of lining ply. The fastener band 15, carrying the row of metallic fasteners 13 is then secured to the folded edge of the cloth 21 by means of a row of vertical stitches 28 which extend through the stiffening ply 23, 65 the lining ply 26, the fastening band 15 and

the fold 22 of the cloth 21 as well as the body of the cloth 21, as shown particularly in Figure 5. The opposed half of the trousers 2 is then finished by folding under the inner edge of the lining 24 as at 29, and securing the same to the cloth 21 by means of a row of vertical stitches 30.

Due to the relatively greater transverse rigidity or stiffness of the front flap 3 and its relatively lesser vertical or longitudinal stiffness, said front flap 3 will lie flat against the opposed half 2 of the trousers in all postures of the wearer so as not only to conceal the fasteners 12 and 13 but so as also to present a neat and dressed appearance 80 at all times.

By means of the novel inner flap 4 the fasteners 12 and 13 are also concealed from within and hence retained out of contact at all times with the body of the wearer or 85 out of contact with undergarments.

Due to the stiffening ply 23 in the inner flap 4, said inner flap 4 will retain its shape while in use and will resist any tendency to be drawn aside and thus to expose the fasteners 12 and 13, due to frictional contact 90 with undergarments or the body.

Due to the novel relation of the fastening means and the construction of the outer flap, said flap will have no tendency to 95 spread open or buckle when the trousers are in use, both of which disadvantages the trousers of present construction so conspicuously possess.

The above novel construction in trousers, 100 not only produce a front closure of a superior quality and appearance, and free of certain defects of trousers made heretofore but said novel construction in trousers also substantially reduces the material and labor 105 heretofore consumed in finishing the front portion of trousers, with a corresponding saving in the ultimate cost thereof.

By the above novel construction in trousers, moreover, the appearance of the front 110 of the trousers is further enhanced by the fact that the outer flap 1 is considerably thinner and is composed of fewer layers or plies than the flaps heretofore employed on trousers, and by virtue of the fact that the 115 buttonhole strip or inner flap as well as the individual buttons are entirely eliminated. It is to be understood that while this novel construction has been described merely in relation to trousers, that the same novel construction is applicable to other garments as well where overlapping edges of two parts of a garment must be fastened and a neat appearance is required.

It should be understood therefore that 125 the characteristic features of this novel construction are the two overlapping flaps 3 and 4, each carrying one half of the fastener; the inner one being suitably stiffened, while the outer one being slightly stiffened 130

longitudinally and greatly stiffened transversely, and having the fastening device spaced a suitable distance inwardly of the free edge thereof, so as to leave said outer stiffened flap free to assume any shape or conformation while in use.

It will now be apparent that we have devised a novel and useful construction which embodies the features of advantage 10 enumerated as desirable in the statement of the invention and the above description and while we have in the present instance shown and described the preferred embodiment thereof which has been found in practice to give satisfactory and reliable results, it is to be understood that the same is susceptible of modification in various particulars without departing from the spirit or 15 scope of the invention or sacrificing any of its advantages.

Having thus described our invention what we claim as new and desire to secure by Letters Patent is:—

1. Trousers or the like, comprising two 25 separable juxtaposed parts having their edges in overlapping relation to each other, a flap formed on each of said edges, a two part continuous and separable fastening device extending longitudinally of said edges; one half of said fastening device being secured to the juxtaposed surface of each of 30 said flaps, spaced a suitable distance inwardly of the free edges of the respective flaps, a textile stiffening ply in the inner flap intermediate of the free edge thereof, and the corresponding half of the fastening device, and an operating slide common to the two halves of 35 said continuous and separable fastening device and slidably carried thereby; said inner flap being adapted to shield said fastening device from contact with the undergarments or the body of the wearer and said outer flap being adapted to conceal said fastening device from view exteriorly.

2. Trousers or the like, comprising two 45 separable juxtaposed parts having their edges in overlapping relation to each other, a flap formed on each of said edges, a two part continuous and separable fastening device extending longitudinally of said edges, one half of said fastening device being secured to the juxtaposed surface of each of 50 said flaps, spaced a suitable distance inwardly of the free edges thereof, a textile stiffening ply in each of said flaps intermediate of the free edge thereof and the corresponding half of the separable fastening device secured thereto, and an operating slide common to the two halves of said continuous 55 and separable fastening device and slidably carried thereby; said inner flap being adapted to shield said fastening device from contact with the body or undergarments of the wearer and the textile stiffening ply in said outer flap being adapted to prevent the separation 60 of the free edge of said outer flap from the juxtaposed part of the trouser when said fastening device is closed.

3. Trousers or the like, comprising two 65 separable parts having their adjacent edges in overlapping relation to each other, thereby forming an outer flap, continuous and separable fastening means extending longitudinally of said flap along the inner face thereof, having one part thereof secured to 70 said outer flap, spaced inwardly a suitable distance from the free edge of said outer flap and having the other part thereof secured to the juxtaposed separable part of the trouser, an operating slide common to the two parts of said continuous fastening means, slidably carried thereby; said continuous fastening means and operating slide being concealed from view by said outer flap, a textile stiffening ply in said outer flap 75 intermediate the continuous fastening means and the free edge thereof, adapted to prevent the separation of said outer flap from the juxtaposed part of the trouser, along the free edge of said outer flap when the fastening means is closed, and an inner flap formed along the free edge of the overlapped portion of the trouser extending beyond the separable fastening means and being adapted to shield the latter from contact with the body and the undergarments of 80 the wearer.

4. Trousers or the like, comprising two 85 separable juxtaposed parts having their edges in overlapping relation to each other, a flap formed on each of said edges, a two part continuous and separable fastening device extending longitudinally of said edges, one half of said fastening device being secured to the juxtaposed surface of each of 90 said flaps, spaced a suitable distance inwardly of the free edges thereof, textile stiffening means in said inner flap; said inner flap being adapted to shield said fastening device 95 from contact with the body and undergarments of the wearer, and a textile stiffening means in said outer flap having greater stiffness transversely of said flap and lesser stiffness longitudinally thereof and being adapted to prevent the separation of the free and unattached edge of said outer flap from the juxtaposed part of the trouser, when said fastening device is closed.

5. Trousers or the like, comprising two 100 separable parts having their adjacent edges in overlapping relation to each other, thereby forming an outer flap, continuous and separable fastening means extending longitudinally of said flap along the inner face thereof, having one part thereof secured to 105 said outer flap, spaced inwardly a suitable distance from the free edge thereof and having the other part thereof secured to the juxtaposed part of the trouser, an operating slide common to the two parts of said continuous fastening means, slidably carried thereby; said continuous fastening means and operating slide being concealed from view by said outer flap, a textile stiffening ply in said outer flap intermediate the continuous fastening means and the free edge thereof, adapted to prevent the separation of said outer flap from the juxtaposed part of the trouser, along the free edge of said outer flap when the fastening means is closed, and an inner flap formed along the free edge of the overlapped portion of the trouser extending beyond the separable fastening means and being adapted to shield the latter from contact with the body and the undergarments of the wearer.

tinuous fastening means, slidably carried thereby; said continuous fastening means and operating slide being concealed from view by said outer flap, a haircloth stiffening ⁵ ply in said outer flap, intermediate of said fastening means and the free edge thereof, said haircloth stiffening ply having strands of a limp character extending longitudinally and being relatively stiffer trans-

¹⁰ versely than longitudinally of said flap, and an inner flap formed along the free edge of

the overlapped portion of the trouser extending beyond the separable fastening means and being adapted to shield the latter from contact with the body and the under-¹⁵ garments of the wearer.

In witness whereof we have hereunto set our hands.

ARTHUR S. LICHTEN.
ABRAHAM KOUFMAN.
WILLIAM SHULIK.
